UNITED STATES PATENT OFFICE.

AUGUST W. WALLMUTH, OF ELGIN, ILLINOIS.

LETTER-SHEET, ENVELOP, AND COIN-HOLDER.

1,306,647.

Specification of Letters Patent. Patented June 10, 1919.

Application filed August 14, 1918. Serial No. 249,859.

To all whom it may concern:

Be it known that I, AUGUST W. WALLMUTH, a citizen of the United States, residing at Elgin, in the county of Kane and State of Illinois, have invented new and useful Improvements in Letter-Sheets, Envelops, and Coin-Holders, of which the following is a specification.

This invention relates to stationery, particularly to letter sheets, and has for its object the provision of a letter sheet formed in the nature of a subscription blank or order sheet, this sheet being foldable upon itself and having certain portions formed to provide flaps whereby the folded sheet may be sealed to form, itself, an envelop, the sheet being further provided with an auxiliary portion foldable to form a pocket for holding coins.

A very important object is the provision of a letter sheet of this character which will be extremely simple and inexpensive in manufacture, highly efficient in use, and a general improvement of the art.

With the above and other objects and advantages in view, the invention consists in the details of construction to be hereinafter more fully described and claimed, and illustrated in the accompanying drawings in which:

Figure 1 is a view of the letter sheet with all its parts in extended positions.

Fig. 2 is a similar view showing a portion of one end of the sheet folded to form a coin holding pocket.

Fig. 3 is a view showing the sheet folded and only the flaps in extended positions and

Fig. 4 is a similar view showing the flaps arranged in their sealing positions.

Referring more particularly to the drawing the numeral 5 designates a sheet of paper which is transversely scored along the lines 6 and 7 to define panels 8 and 9. Flaps 10 are formed upon the ends of the panel 8 by scoring the panel 8 along the line 11. A flap 12 is formed on one longitudinal edge of the panel 8 and extends from the line of scoring 6. The panel 8 together with the flaps 10 and 12 coöperates with the panel 9

for forming an envelop as will be herein- 50 after described.

The panel 9 is scored upon the line 13 to provide an auxiliary panel 14 which is scored along the diagonal lines 15 as shown. This auxiliary panel 14 is designed to be 55 folded to form a coin holding pocket.

It will be understood of course that the letter sheet may be used for any desired purpose, so in the present instance I have shown the panel 9 as formed in the nature 60 of a subscription or order blank. Any desired matter may appear upon the panel 8, of course, and the other side of the panel 8 is adapted to bear the address.

In order that the letter sheet may be used 65 as a coin holder, the auxiliary panel 14 is folded upon itself along the lines 15 to define a triangular pocket, as shown in Fig. 2. The coins may then be inserted within this pocket, after which the pocket is folded over 70 along the line 13 to lie upon the panel 9. In order to seal the device, the panel 9 together with the coin holding pocket is folded over upon the panel 8, after which the flaps 10 and 12 are folded over upon the 75 panel 9 along the lines 11 and 6 as clearly shown in Fig. 4, it being understood of course that the flaps 10 and 12 are gummed. The device when thus folded and sealed will 80 present the appearance of an ordinary envelop and will effectually retain the coins disposed therein so that loss thereof will be prevented.

From the foregoing description and a study of the drawings it will be apparent 85 that I have thus provided in a single sheet a combined subscription or order blank, coin holding pocket and envelop.

What is claimed is:

A device of the character described comprising a sheet of material transversely scored to provide a plurality of panels and a flap, the panel opposite the flap being longer than the other panel, the panel adjacent said flap being scored at right angles 95 to said first named lines of scoring to produce end flaps, the other of said panels being scored at one side in alinement with one

of said second named lines of scoring to provide an auxiliary panel disposed at one side of the second named panel said auxiliary panel being scored along diagonally intersecting lines to provide flaps, said last named flaps being foldable one upon the other to provide a substantially triangular pocket, foldable laterally onto said second

named panel, said second named panel being foldable onto said first named panel and said first and second named flaps being foldable onto said second named panel to provide a closure.

In testimony whereof I affix my signature

AUGUST W. WALLMUTH.
